Specification for Design.

Patented Mar. 20, 1917.

Application filed December 2, 1916. Serial No. 134,766. Term of patent 3½ years.

To all whom it may concern:

Be it known that I, FRANK YOKEL, a citizen of the United States, residing at Pittsburgh, in the county of Allegheny and State of Pennsylvania, have invented a new, original, and ornamental Design for a Back for Blotters, Paper-Weights, or Similar Articles, of which the following is a specification, reference being had to the accompanying drawing, forming part thereof.

Figure 1 is a top plan view of the back for blotters, paper weights and similar articles illustrating my new design; and

Fig. 2 is a side elevation of the same.

I claim:—

The ornamental design for a back for blotters, paper weights or similar articles, as shown.

FRANK YOKEL.
